UNITED STATES PATENT OFFICE.

CHARLES BENJAMIN REDRUP, OF CANTON, CARDIFF, ENGLAND.

CYLINDER FOR FLUID-PRESSURE ENGINES OR PUMPS.

1,030,681.

Specification of Letters Patent. Patented June 25, 1912.

Application filed August 10, 1911. Serial No. 643,456.

To all whom it may concern:

Be it known that I, CHARLES BENJAMIN REDRUP, a subject of the King of England, residing at Canton, Cardiff, in the county of 5 Glamorgan, England, have invented certain new and useful Improvements in Cylinders for Fluid-Pressure Engines or Pumps, of which the following is a specification.

This invention is for improvements in or 10 relating to cylinders for fluid-pressure engines or pumps and has particular reference to internal combustion engines of the type wherein two or more cylinders are carried by a revolving crank-case, the cylinders being disposed radially relatively thereto.

The invention has for its object to provide a light engine which can be cheaply constructed and to this end one feature of the invention consists in employing with a 20 cylinder of thin tubular material a shell of similar material of such diameter as to provide a space between it and the cylinder proper to receive one or more valves of the sleeve type.

25 By building each cylinder and shell of tubing providing a smooth exterior surface having no projecting parts, it can be passed through an orifice in the crank-chamber from within the latter and secured in place, 30 for example, by a shoulder provided on the part of the shell that lies within the crank-case and a nut that engages a screw-thread on that portion of the shell which lies outside the crank-case.

35 In the accompanying drawings which illustrate one method of carrying out this invention as applied to a rotary cylinder engine:—Figure 1 is a section through the crank-case of a three-cylinder engine in the 40 plane of the crank-shaft; Fig. 2 is a section through the crank-case at right angles to the crank-shaft with one of the cylinders also in section, and Fig. 3 is a perspective view of one of the valves.

45 Like letters indicate like parts throughout the drawings.

The cylinders are disposed radially around and project inwardly of the crank-chamber A which is free to rotate upon the 50 crank-shaft B. Each cylinder C is built of thin tube presenting a plain exterior surface. The part C constitutes the cylinder proper and surrounding this for its entire length is a shell D also formed of this tube. 55 The shell D is of larger diameter than the cylinder C so that a space D¹ is provided be-

tween them wherein two valves E, each of semi-circular form as shown in Fig. 3, are mounted. The cylinder C and the shell D are kept in proper relation to each other by 60 a head F that is screw-threaded at F¹ to engage a screw-threaded enlargement or ring C¹ in the end of the cylinder. The head F has a peripheral shoulder F² that extends over an inwardly directed flange D² on the 65 end of the shell D. This flange extends inwardly over the end of the cylinder proper C and is thus clamped by the head F against the end of the cylinder, the head also serving to centralize the shell relatively to the 70 cylinder. The space thus provided between the shell and the cylinders accommodates, as already stated, the valve E and at the crank-chamber end of the cylinder is a 75 flange or distance-piece C² that serves to maintain the relative position of these two parts at that end. Packing can be introduced at C³ between this enlargement and the inner face of the wall of the shell D.

At the head end of the cylinder ports C⁴ 80 are provided for inlet and exhaust and opposite these are ports D³ in the shell D. These ports are covered and uncovered by the valves E. The inlet and exhaust conduits for communicating with the ports and 85 the mechanism for moving the valves are not shown in the drawings and need not be described as they form no part of the present invention.

In bringing the cylinders into position 90 each cylinder after having the valves introduced in place and the shell secured by the head F, is introduced through one of the three orifices A¹ in the crank-case and the exterior of the shell D with the head F being 95 smooth with no projecting parts enables this to be done easily without the orifices having to be slotted or shaped otherwise than circular. The shell D is provided with a thickened portion D⁴ that is screw-threaded to receive a nut D⁵ and carries a flange D⁶. The flanges on that side of the shell which lies within the crank-case thus serve as an abutment against which the cylinder is positioned and the nut D⁵ is then screwed on to the shell outside the crank-case thereby locking the parts rigidly to the crank-case. Each shell D is slotted at D⁷ to permit lugs E¹ on the valves E to extend through them 100 for connection to the valve operating mechanism.

Cylinders built up in the manner described

with an exterior shell formed of thin material are cheaply and easily manufactured and the head F constitutes a simple and effective means for connecting the parts and 5 sealing the head ends of the space D¹.

It will be seen that the flange D⁶ on each shell takes the whole centrifugal thrust of the shell and cylinder with its associated parts and is eminently adapted for this 10 purpose.

What I claim as my invention and desire to secure by Letters Patent is:—

1. In an engine cylinder, the combination of an inner cylinder open at either end; a 15 shell surrounding said cylinder and spaced therefrom to provide a valve working chamber, said shell having an inwardly disposed annular flange at one end thereof overlying the edge at one end of said inner cylinder; a head closing one end of said inner cylinder, said head having a screw-threaded flange in engagement with said inner cylinder, and engaging with the inturned flange 20 at the end of said shell; and a valve mounted in said valve working chamber, substantially as described.

2. In an engine cylinder, the combination of an inner cylinder open at either end, and provided with a screw-threaded end portion; a shell surrounding said inner cylinder and spaced therefrom to provide a valve working chamber, said shell having an annular flange 30 at the end opposite the screw-threaded end of the inner cylinder engaging with said inner cylinder and holding said shell and said inner cylinder in concentric relation, and having at its opposite end an inwardly disposed flange overlying the screw-threaded portion of said inner cylinder.

der; a head closing one end of said inner cylinder, said head having a screw-threaded flange engaging with the screw threads of 40 said inner cylinder, and having a peripheral shoulder overlying the annular inturned flange of said shell; and a valve mounted in 45 said valve working chamber, substantially as described.

3. In a fluid-pressure engine, the combination of a revoluble casing provided with apertures; a plurality of radially disposed 50 cylinders located within said body and projecting therethrough, each of said cylinders comprising an inner cylindrical body and a surrounding outer shell, each of said shells having an annular flange and a screw-threaded portion, said flange adapted to abut against the inner edge of the revoluble casing; a ring having engagement with the screw-threaded portion of each shell and cooperating with said annular flange to clamp 55 the cylinder to said casing; said shell having an inwardly disposed flange overlying the outer edge of the cylindrical body; a cylinder head having screw-threaded engagement 60 with the cylindrical body and clamping said shell thereto through the medium of said overlying flange; valves operable between said shell and said cylindrical body; pistons operable in said cylinders; and operative 65 connections between said valves and said pistons, substantially as described.

In testimony whereof I have signed my name to this specification in the presence of two subscribing witnesses.

CHARLES BENJAMIN REDRUP.
